UNITED STATES PATENT OFFICE.

CARL J. SCHWARZE, OF ADRIAN, MICHIGAN, ASSIGNOR TO SCHWARZE ELECTRIC COMPANY, OF ADRIAN, MICHIGAN, A CORPORATION OF MICHIGAN.

ELECTRIC BELL OR LIKE DEVICE.

No. 799,016.

Specification of Letters Patent.

Patented Sept. 5, 1905.

Application filed May 31, 1904. Serial No. 210,475.

To all whom it may concern:

Be it known that I, CARL J. SCHWARZE, a citizen of the United States, residing at Adrian, in the county of Lenawee and State of Michigan, have invented a certain new and useful Improvement in Electric Bells or Like Devices, of which the following is a full, clear, concise, and exact description, reference being had to the accompanying drawings, forming a part of this specification.

My invention relates to electric call-bells and like devices, and particularly to a construction thereof involving a pair of electromagnets arranged side by side and a vibratory armature actuated by said magnets.

Prominent objects of the invention are to provide a durable and inexpensive construction of devices of this kind, to increase to the maximum the efficiency of operation, and to accomplish the above results in a practical and expeditious manner.

The present invention is shown embodied in a vibratory call-bell, although it is understood that it can be embodied in other devices of the same general character as well.

In the accompanying drawings, Figure 1 is a front elevation of a vibratory call-bell embodying the invention. Fig. 2 is a top plan of the same, and Fig. 3 is a diagrammatic view of a part of the bell and its circuit connections.

The device which is shown in the drawings for carrying out the invention comprises a frame conveniently consisting of an upper strip or plate 1, a pair of side rods 2 2, secured to the ends of the plate 1 by nuts 3 3, and magnet supports or holders 4 4, fitted on the lower ends of the rods 2 2 and secured thereto by nuts 5 5. The magnet-supports 4 4 are made of magnetic material, preferably iron, and are provided with upwardly-extending ends or portions 6 6, which are secured together and held in position by a strip 7 of non-magnetic material, preferably brass. The side rods 2 2 are also of non-magnetic material, such as brass, while the top plate 1 is of magnetic material, preferably iron. A pair of electromagnets 8 and 8^a are mounted on the magnet-supports 4 4 and held properly in position by means of screws 9 9. The top plate 1 is provided with front and back overhangs 10 and 11, and a vibratory armature 12 is pivotally supported by such overhangs. This general construction of frame and mag-

nets, it will be seen, provides an arrangement 55 by which two nearly or substantially closed magnetic circuits are provided for the two magnets, each of these consisting of a magnet-core, a portion of the member 4, the upright 6 thereof, and the portion of the armature 12 between such upright and the magnet-core. The insulating-strip 7 separates the magnetic circuits of the two magnets, whereby the efficiency and effectiveness of the device is greatly enhanced. Furthermore, the 60 side rods 2 2 effectively complete and brace the frame, and as they are of non-magnetic material no leakage of magnetic lines of force occurs in or through them.

In an application filed by me July 25, 1902, 70 Serial No. 117,032, I show and describe an electric vibratory call-bell having certain novel features of construction and operation, and in the present application I show certain of the broader features of the invention of 75 said other application applied to the present and hereinabove set forth construction, although it will be understood that said construction is useful in connection with other arrangements. To operate in accordance with 80 the invention of my said other application, the armature 12 is provided with a metallic strip 13, the opposite ends of which are adapted to provide contacts. A pair of contact-screws 14 and 14^a is mounted in the top 85 plate 1, but insulated therefrom by insulating-disks 15 15 and threaded bushings 16 16, extended through the same. Set-nuts 18 18 are provided for the attachment of conductors. The contact-screws 14 and 14^a are mounted 90 in such position that their lower ends, which project through the top plate 1, the insulation 15, and the threaded bushing 16, are over the opposite ends of the contact-strip 13. They are so adjusted that when the armature 12 is 95 vibrated to one side—for example, with its right-hand end down and its left-hand end up, as shown in Fig. 1—the contact-strip 13 will make contact with the screw 14 and be out of contact with the screw 14^a, whereas 100 when the armature is vibrated to an opposite position the strip 13 will make contact with the screw 14^a and be out of contact with the screw 14. A wire connection 12^a is shown 105 extended between the top 1 and the armature 12 to insure good electrical connection between said armature and the frame of the device. The armature 12 carries a pendant or

arm 20, provided with a ball or knob 21 for striking the bell.

The coils 22 and 22^a, Fig. 3, of the magnets 8 and 8^a are connected in shunt with the circuit 25, which is shown as an operating-circuit for operating the bell. This shunt connection consists in connecting the two coils with one another and with the opposite sides of the circuit and also in connecting said opposite sides of the circuit by conductors 24 and 24^a with the contact screws 14 and 14^a. The armature 12 in vibrating causes its contact-strip 13 to make and break connection with the contact screws 14 and 14^a, whereby first one magnet and then the other is energized. The circuit 25 is shown with a push-button 28 for closing the circuit through the bell. The magnets 8 and 8^a are provided with closed or short-circuited induction-coils 26, which tend to suppress sparks in the operation of the device and increase the efficiency of its operation.

It will be understood that changes and modifications can be made in the device herein shown without departing from the spirit of my invention, and, furthermore, that the invention herein set forth can be applied to devices other than call-bells, as herein shown.

What I claim as my invention is—

- 30 1. The combination with a pair of magnetic devices arranged side by side, of an armature therefor, means for forming continuous magnetic return-paths around said magnetic devices, open at said armature, and a strip of 35 non-magnetic material interposed between the means forming said magnetic paths, substantially as described.
2. The combination with a pair of electromagnets, of bars of magnetic material connected with the cores thereof and extended lengthwise of the magnets between the same, a strip of non-magnetic material interposed between said bars, and an armature for said electromagnets, substantially as described.
- 45 3. The combination with a pair of electro-

magnets arranged side by side, of a vibratory armature therefor, bars of magnetic material connected with the cores of said magnets, and extended lengthwise of the magnets between the same, a strip of non-magnetic material interposed between said magnets and the bars between the same, means for changing the circuit connections so as to cause the said magnets to vibrate said armature, and closed secondary coils on said magnets, substantially as described.

4. The combination with a pair of electromagnets, of an armature, supports for said magnets, which supports are made of magnetic material and provided with portions extending between the magnets and forming continuous magnetic return-paths to the armature, non-magnetic material interposed between said magnetic paths, and a frame carrying said magnetic supports, the parts of 65 said frame connected therewith being of non-magnetic material, substantially as described.

5. The combination of a pair of electromagnets arranged side by side, a vibratory armature therefor, supports for said magnets, 70 consisting of bars of magnetic material connected with the cores of said magnets, and extended lengthwise between the same to substantially the armature, a strip of non-magnetic material interposed between the longitudinally-extending portions of said magnet-supports, a frame comprising a top carrying said armature, rods of non-magnetic material connecting said top and said magnet-supports, and co-operating contact members on the top 8c and on said armature for controlling the circuit connections to said magnets to cause the vibration of the armature, substantially as described.

In witness whereof I hereunto subscribe my 85 name this 9th day of May, A. D. 1904.

CARL J. SCHWARZE.
